(57) **CLAIM**

We claim the ornamental design for a wireless power transfer pad, as shown and described.

DESCRIPTION

FIG. 1 is a top right perspective view of a wireless power transfer pad showing the design;

FIG. 2 is a front elevation view thereof;

FIG. 3 is a top plan view thereof;

FIG. 4 is a rear elevation view thereof;

FIG. 5 is a left elevation view thereof;

FIG. 6 is a bottom plan view thereof; and,

FIG. 7 is a right elevation view thereof.

The broken lines depict portions of the wireless power transfer pad that form no part of the claimed design.

1 Claim, 3 Drawing Sheets
